UNITED STATES PATENT OFFICE.

WILLIAM E. ROBERTS, OF NEW YORK, N. Y., ASSIGNOR, BY MESNE ASSIGNMENTS, TO FOUNDATION OVEN CORPORATION, OF NEW YORK, N. Y., A CORPORATION OF NEW YORK.

AIR-VALVE FOR COKE-OVEN OR THE LIKE.

1,395,060.

Specification of Letters Patent. Patented Oct. 25, 1921.

Application filed February 7, 1919. Serial No. 275,632.

To all whom it may concern:

Be it known that I, WILLIAM E. ROBERTS, a citizen of the United States, residing in the city, county, and State of New York, have 5 invented certain new and useful Improvements in Air-Valves for Coke-Ovens or the like, of which the following is a specification.

In by-product coke ovens and similar apparatus operating in conjunction with a regenerator air is admitted from the atmosphere to a port of the regenerator whence it passes through the regenerator to combustion chambers or flues in or around the 10 ovens and thence the hot combustion products pass through a second regenerator and to outlet flues connected to a stack or exhaust fan; and after a period of time the valve connections are reversed so that air from the atmosphere is admitted to the second regenerator and passes through the combustion chambers and the combustion gases pass back through the first regenerator and out through the port which was previously 15 its inlet and thence to the exhaust flue. The valves for controlling the air connections have given considerable difficulty, being subjected alternately to the comparatively cold atmospheric air passing into the port of the 20 regenerator and to the very hot products of combustion passing out from the regenerator to the exhaust flue, and being subject to a temperature and to variations of temperature which in the course of time distort it 25 and cause leaks and difficulty in operation. To avoid these difficulties a great many expedients have been adopted and in many cases two valves have been used for each regenerator port, one for merely admitting 30 or cutting off atmospheric air and the other for admitting or cutting communication with the exhaust flue; and the various valves of this and other sorts which have been used have been complicated in design and expensive to construct and maintain in good order.

My invention presents a valve, the parts of which are simple in design and cheap to manufacture and maintain in order or to replace when they become defective through

use, and which are very reliable in operation.

The accompanying drawings illustrate embodiments of the invention.

Figure 1 is a longitudinal section of a 55 valve mounted in connection with ports of a regenerator and an exhaust flue;

Fig. 2 is a cross-section of the same;

Fig. 3 is an end view of the branch of the valve which communicates with the regenerator;

Fig. 4 is a horizontal section on the line 4—4 of Fig. 1;

Fig. 5 is a plan of an air damper for controlling the admission of atmospheric air; 60

Figs. 6 to 9 illustrate another construction; Fig. 6 being a longitudinal section, Fig. 7 an end view of the casing, Fig. 8 an opposite end view of the valve and operating mechanism and Fig. 9 a plan of the 70 same.

Referring first to the embodiment of the invention illustrated in Figs. 1 to 5, the valve A has a lateral branch B communicating with the port C through a wall D of the 75 regenerator, and has a downward branch E communicating with a port F of the exhaust flue G.

The branch B of the valve body is rectangular in cross-section to make an easier connection with a rectangular port in the brick wall of the regenerator. Its upper side is formed with a slot H through which a plate or damper J may be passed to adjust the open cross-section as desired, this branch being provided also with ribs L engaging the rear face of the plate J and holding it against the outward suction. The damper J can be raised or lowered to any desired position and fastened there by any usual or suitable means such, for example, as the pin shown passing through one of a series of holes therein. Such a damper is used on the several valves of an installation to compensate for the differences in suction on the different valves by reason of their relative locations along the flue.

At the upper and lower ends of the valve chamber are cylindrical seats or bearings M and N turned or ground to make a 100

fit with the valve body as the temperature variations will permit.

The valve body comprises two cylindrical portions O and P continuous with each other 5 and divided by a transverse diaphragm Q across the interior. The valve body is formed also with an upper head R and a lower head S and these heads and the diaphragm are cast on a central hollow shank 10 T through which passes a rod or stem U having a shoulder V at its upper end and a nut W at its lower end by which the valve body is fastened on it.

The upper head R of the valve body has 15 openings through it to the atmosphere and the upper cylindrical portion O has lateral openings. When the valve body is elevated to the position shown or higher the lateral openings therethrough are out of communication with the valve chamber. But when it is lowered below this position these lateral openings communicate with the valve chamber and air passes from the atmosphere through such openings into the branch B 20 and the port C of the regenerator. The cylindrical surface of the valve body is extended below the lower head thereof by means of wings X which maintain a proper bearing in the seat N when the valve is lifted 25 above the position shown.

The lower head S of the valve is imperforate and therefore in the position shown or in any lower position serves to cut off communication between the regenerator and 30 the exhaust flue. But when the valve is elevated above the position shown, so that the lower head S passes above the seat N, a passage is opened below the lower head and between the wings X by which the products 35 of combustion can pass from the regenerator and through the parts B and E of the valve casing to the exhaust flue.

Various devices for raising and lowering the valve stem may be adopted. I have 40 shown a bearing block Y mounted on a lateral extension of the valve casing and carrying a lever having an arm Z which is connected through a link 2 to the upper end of the stem U and having an arm 3 which is 45 actuated by a rod 4 passing through a crotch in the upper end of the arm 3 and having suitable collars such as 5 thereon which strike the arm 3 and actuate the valve in one direction or the other as the rod is moved 50 to the right or to the left. Such an operating rod is usually provided and extends to an interlocking system to insure the opening and closing at proper relative times of the different valves of an oven.

60 For regulating the quantity of air admitted through the upper head R an air plate 6 is mounted to turn on the center T of the valve and is provided with openings 7 adapted to register more or less with the openings 65 in the head R of the piston as the plate

is turned. Holes 8 are provided through which a pin q (Fig. 1) may be dropped in a hole drilled in the edge of the valve body, so as to hold the plate against accidental displacement.

The inlet port communicating with the atmosphere is at the side of the casing opposite to that of the outlet through which the hot gases of combustion pass to the flue so as to minimize the effect of the difference in 70 temperature of the air and the combustion gases respectively. The casing is simple in design and provides an abundant cross-section for the free flow of air and gases. All the parts are easily accessible for withdrawal for repair or replacement.

The parts are easily accessible for withdrawal for repair or replacement.

In Figs. 6 to 9 I have shown a modified form of my valve specially useful for particular cases. For greater compactness the valve casing 9 is made of less height, with 80 an oblong branch 10 which communicates with the regenerator through a section of piping 11 oblong at one end to fit the valve casing and extending upward and squared at its opposite end where it communicates 85 with the port C of the regenerator D. The casing is also provided with a downwardly depending guide flange 12 to form the upper bearing for the valve body, its lower bearing N being the same as in Fig. 1. The valve 90 body is likewise reduced in height comprising a cylindrical portion 13 with depending guide wings 14 which engage the lower bearing N when the valve is in the raised, exhausting position of Fig. 6. The upper part 100 of the cylindrical portion of the valve body is provided with openings 15 which in the elevated position of the valve extend above the casing 9. The top of the valve is open and, when it is lowered to close the exhaust 105 port, air passes through the top of the valve body and through the side openings 15 into the regenerator.

Within the upper part of the valve body is an air regulating ring 16 provided with 110 openings 17, which, by the turning of the ring, can be caused to register more or less with the openings 15 of the valve to regulate the quantity of air admitted.

This construction has an advantage over 115 that of Figs. 1 and 5 in permitting the valve to be designed for the maximum volume of air desired, without increasing its diameter. By making the height of the openings 15 and 17 correct the volume of air can be 120 increased to the full capacity of the cross-section of the cylindrical valve through which the air enters; whereas with a regulator of the type shown in Fig. 5 only a fraction of this cross-section can be used.

With this comparatively flat style of casing I may also arrange the operating mechanism so as to require only a small space, not extending substantially above the top of the pipe 11 leading to the regenerator. The 125 130

details of this operating mechanism are shown in Figs. 8 and 9. The stem U of the valve is connected at its upper end through a link 18 to an arm 19 on a shaft 20 mounted on a bracket 21 on the top of the valve casing 9 and carrying a downwardly extending arm 22 which is engaged by the rollers 5 on the operating rod 4.

Fig. 6 shows the exhausting position of this valve. It can be lowered until the cylindrical portion 13 of the valve just spans the distance between the depending bearing flange 12 and the lower bearing N, cutting off both air and combustion gases. Or by lowering it still further air is admitted through the top of the valve and through the ports in the regulator and in the upper part of the cylinder to pass to the regenerator.

Though I have described with great particularity of detail certain embodiments of my invention, yet it is not to be understood therefrom that the invention is restricted to the exact designs shown. Various modifications thereof may be made by those skilled in the art without departing from the invention as defined in the following claims.

What I claim is—

1. An air valve for coke ovens or the like comprising a casing with branches communicating with a regenerator port and an exhaust flue respectively and having a valve chamber with cylindrical bearings or seats at opposite sides and a hollow cylindrical valve body sliding in said bearings, having an end open to the atmosphere and having lateral openings and adapted in one position to admit air from the atmosphere past one of said bearings to the regenerator and in another position to admit gases of combustion from the regenerator past the other bearing to the exhaust flue.

2. An air valve for coke ovens or the like comprising a casing with branches communicating with a regenerator port and an exhaust flue respectively and having a valve chamber with cylindrical bearings or seats at opposite sides and a cylindrical valve body sliding in said bearings and adapted in one position to admit air from the atmosphere past one of said bearings to the regenerator and in another position to admit gases of combustion from the regenerator past the other bearing to the exhaust flue and a regulator for controlling the volume of air admitted.

3. An air valve for coke ovens or the like comprising a casing with branches communicating with a regenerator port and an exhaust flue respectively and having a valve chamber with cylindrical bearings or seats at opposite sides and a cylindrical valve body sliding in said bearings, said valve having open ends and having one set of lateral passages opening to the atmosphere and

to the valve casing in one position and another set of lateral passages opening to the exhaust flue and to the valve casing in another position, the two sets of passages being independent.

4. An air valve for coke ovens or the like comprising a casing with branches communicating with a regenerator port and an exhaust flue respectively, said casing having its opposite walls formed with cylindrical bearings or seats and a cylindrical valve body sliding in said bearings and adapted in one position to admit air from the atmosphere past one of said bearings to the regenerator and in another position to admit gases of combustion from the regenerator past the other bearing to the exhaust flue, the seat through which air is admitted being formed by a flange depending within the casing.

5. An air valve for coke ovens or the like comprising a casing with branches communicating with a regenerator port and an exhaust flue respectively and having a valve chamber with cylindrical bearings or seats at opposite sides and a cylindrical valve body sliding in said bearings and adapted in one position to admit air from the atmosphere past one of said bearings to the regenerator and in another position to admit gases of combustion from the regenerator past the other bearing to the exhaust flue, said valve body having a transverse wall and having an open end and openings through its side between said end and said transverse wall.

6. An air valve for coke ovens or the like comprising a casing with branches communicating with a regenerator port and an exhaust flue respectively and having a valve chamber with cylindrical bearings or seats at opposite sides and a cylindrical valve body sliding in said bearings and adapted in one position to admit air from the atmosphere past one of said bearings to the regenerator and in another position to admit gases of combustion from the regenerator past the other bearing to the exhaust flue, said valve body having a diaphragm and having an open upper end and openings through its side above said diaphragm, and an air regulator consisting of a ring fitting the upper portion of said valve body and having openings adapted to be turned to register more or less with the openings in the valve body.

7. An air valve for coke ovens or the like comprising a casing having a valve chamber with cylindrical bearings or seats at opposite sides and an open-ended hollow cylindrical valve body sliding in said bearings, provided with lateral openings and adapted in one position to admit air to the regenerator and in another position to admit gases of combustion from the regenerator to the exhaust flue.

8. An air valve for coke ovens or the like comprising a casing having a valve chamber with cylindrical bearings or seats at opposite sides and a cylindrical valve body sliding in said bearings and adapted in one position to admit air to the regenerator and in another position to admit gases of combus-

tion from the regenerator to the exhaust flue, said body having a transverse wall, an open end and openings through its side communicating with the end opening.

In witness whereof, I have hereunto signed my name.

WILLIAM E. ROBERTS.
